(57) **CLAIM**

The ornamental design for a shoe, as shown and described.

DESCRIPTION

FIG. 1 is a front perspective view of a shoe showing our new design;

FIG. 2 is a side view thereof;

FIG. 3 is a rear view thereof;

FIG. 4 is an opposite side view thereof;

FIG. 5 is an opposite side front perspective view thereof; and,

FIG. 6 is a front view thereof.

The even-length zig-zag broken lines shown on the straps represent stitching and form no part of the claimed design. The uneven-length broken line elements and the unshaded regions therein, including the latch features and pull-tabs, form no part of the claimed design. The uneven-length broken lines depicting the remainder of the shoe show features that form no part of the claimed design.
